OCCUPANT PROPELLED ROUNDABOUT

Foster C. Wilson, Baltimore, Md., and
Charles C. Napolitan, Johnstown, Pa.

Application July 13, 1948, Serial No. 38,528

4 Claims. (Cl. 272—33)

1

This invention relates to a game apparatus of the type known as a roundabout and it is one object of the invention to provide a device of this character wherein a spinner of improved construction is rotatably mounted about a post rising from a base, the spinner having seat-carrying arms extending from a hub or sleeve and braced against downward strains to which they are subjected by the weight of persons occupying seats at outer ends of the arms.

Another object of the invention is to provide arms and braces which are formed of bars or strips of angle metal and are, therefore, of light weight but very strong.

Another object of the invention is to provide a roundabout formed of companion elements which are bolted together, thus allowing the device to be shipped or stored in knocked-down condition and easily assembled for use.

Another object of the invention is to so form the base from which the post extends that the post will be firmly supported and prevented from tilting out of an upright position during use of the roundabout.

Another object of the invention is to provide improved means for imparting turning movement to the spinner about the post, the said operating means including a lever pivoted to one of the arms of the spinner in such position that it may be readily grasped by a person occupying the seat at the outer end of this arm.

With these and other objects in view the invention consists of an improved construction and arrangement of parts illustrated in the accompanying drawings wherein:

Fig. 1 is a top plan view of the improved roundabout.

Fig. 2 is a side view thereof.

Fig. 3 is a sectional view upon an enlarged scale taken vertically along the line 3—3 of Fig. 1.

Fig. 4 is a fragmentary view showing a portion of the arm carrying the operating lever partially in elevation and partially in section.

Fig. 5 is a fragmentary view showing the outer end portion of an arm and a seat carried thereby in side elevation.

Fig. 6 is a view showing the seat and the outer end portion of the arm in section.

Fig. 7 is a perspective view of the upper portion of the post and a lever carried thereby.

This improved roundabout has a post 1 supported in an upright position by a base indicated in general by the numeral 2. This base includes legs 3 which are formed of angle metal and are of elongated triangular shape when viewed in side elevation and at their outer ends are provided with feet 3' formed of heavy metal. Since the blocks forming the feet 3' extend downwardly below the lower edges of the legs 3, the legs will be held out of contact with the ground upon which the feet rest and the feet may have good biting engagement with the ground to prevent slipping of the base along the ground out of a predetermined position. A sleeve 4 fits snugly about the lower portion of the post 1 and is surrounded by an outer sleeve or collar 5, and upon referring to Fig. 3 it will be seen that the collar 5 is formed with openings 6 which register with threaded openings 7 formed in the sleeve 4 so that screws 8 which are passed through the inner ends of the legs 3 may be screwed into the openings 7 and firmly secure the legs to the collar 5 in radiating relation thereto. The upper end of the collar projects above the sleeve 4 and is formed with a recess 9 constituting a seat for a thrust bearing 10 which surrounds the post 1. Since the screws pass through the aligned openings of the collar 5 and the sleeve 4, their inner ends will have abutting engagement with the post 1 and serve as set screws to firmly hold the post against vertical or turning movement.

The spinner has at its center a vertical sleeve 11 which is of appreciably greater diameter than the post 1 and fits loosely about the post. A bushing 12 fits tightly within the lower end of the sleeve 11 and its lower end is radially enlarged to form a cup 13 into which fits the upper disk of the thrust bearing 10. Therefore, the sleeve or hub 11 of the spinner may turn freely about the post. In the upper end of the sleeve 11 is a bushing 12'. A rectangular plate 14 is welded flat upon the upper end of the hub 11 and at its center is formed with a circular opening 15 through which projects the upper end portion of the post 1, the upper end of the post being reduced in diameter and squared to form a neck 16 for receiving a ratchet member 17 loosely mounted through the inner end of a lever 18. Since the neck 16 passes through a squared opening in the ratchet member 17, turning of the ratchet member about the post will be prevented and as the lever is provided with a spring pressed pawl 19 for engaging teeth of the ratchet member the lever may be moved about the ratchet member 17 and the post in step-by-step movements in one direction and held against swinging movement in the opposite direction. A cap 20 which fits upon the upper end of the neck 16 and is secured by a screw 21 holds the ratchet member and the lever upon the neck.

2

Arms 22 extend from the hub 11 radially thereof and each has side bars 23 connected at their outer ends by a bridge portion 24. Angle metal is used for forming the arms and since flanges of the angle metal strips extend downwardly along outer side edges of their side bars 23 and bridge portions 24, the arms will be braced against crumpling. Near their outer ends the bars 23 are bent downwardly and then outwardly to form downwardly offset saddle portions 25 to which seats 26 are secured by bolts 27. The side bars 23 spread towards their inner ends so that inner ends of the arms 22 are of only slightly less width than the length of a side edge of the plate 14 and end portions of their depending side flanges are cut off so that inner ends of the side bars may be disposed in overlapping engagement with the plate and firmly secured thereon by bolts 28 as shown in Figure 3.

Bracing bars 29 are mounted across the side bars 23 at the junction of inner ends of the saddles 25 with the downwardly extending portions 30 of the side bars and have their ends welded or otherwise firmly secured. To these cross bars 29 are applied bracing bars 31 which are also formed of angle metal and have their outer ends secured to the cross bars by bolts 32 and their inner ends secured by screws 33 which pass through the lower end of the sleeve or hub 11 and into threaded openings formed in the bushing 12. The braces 31 extend diagonally at an upward incline towards their outer ends and very effectively prevent the arms 22 being bent downwardly by the weight of occupants of the seats 26. Diagonally extending braces 34 are mounted between inner end portions of the arms 22 and prevent the arms from having side play upon the plate 14. Foot rests 35 are mounted across the bracing bars 31 in such spaced relation to their outer ends that occupants of the seats may conveniently rest their feet upon them, and there have also been provided handle bars 36 which extend across the arms and are secured to the side bars 23 thereof by bolts 37. The handle bar carried by one arm 22 is cut off and in advance of this handle bar is a lever 38 which extends transversely across the arm and has its inner end pivotally connected with one side bar 23 thereof by a bolt 39 and its outer end provided with a hand hold 40. A strip 41 carried by the arm and extending longitudinally thereof and across the lever 38 guides movement of the lever and a pitman rod 42 connects the outer end of lever 38 with the operating lever 33 inwardly of the hand hold 40. This is shown in Fig. 1 and upon referring to this figure, it will be seen that when the hand hold is grasped by a person occupying the seat 26 of the arm to which the lever 38 is mounted and oscillating movement applied to the lever, similar movement will be transmitted to the lever 33 and the lever 33 moved about the ratchet member.

During pull upon the operating lever 33 the spinner will be rotated about the post and by rapidly moving this lever the speed at which the spinner turns may be increased until it has a continuous turning movement about the post 1.

From the foregoing description of the construction of my improved device, the operation thereof and the method of assembly will be readily understood, and it will be seen that I have provided a comparatively simple, inexpensive and efficient means for carrying out the various objects of the invention.

While I have particularly described the elements best adapted to perform the functions set

forth, it is apparent that various changes in form, proportion and in the minor details of construction may be resorted to, without departing from the spirit or sacrificing any of the principles of the invention.

Having thus described the invention, what is claimed is:

1. A roundabout comprising a base including a sleeve and legs radiating from the sleeve, a bushing in said sleeve, screws passing through inner ends of the legs and into threaded openings formed in the bushing, a post mounted vertically through said bushing and gripped by inner ends of said screws, a thrust bearing surrounding the post and seated in a recess formed about the upper end of said sleeve, and a spinner including a tubular hub fitting loosely about said post, a bushing in the lower end portion of said hub having at its lower end a cup fitting about the thrust bearing and confining the same in its seat, arms extending radially from said hub, seats carried by said arms, and means actuated by an occupant of a seat for turning the spinner about the post.
2. In a roundabout, a vertical post, and a spinner comprising a tubular hub loosely mounted about said post, a head plate at the upper end of said hub, arms extending radially of the post and each having transversely spaced side bars connected at their outer ends by a bridge and having their inner ends secured to the head plate, said side bars being bent in spaced relation to their outer ends to form portions extending downwardly at an outward incline and a horizontal saddle projecting outwardly from lower ends thereof, seats upon said saddles, handle bars mounted across said arms inwardly of the downwardly bent portions of their side bars, bracing bars secured at inner ends to the lower end portion of said hub and extending outwardly at an upward incline and having their outer ends secured to cross bars extending transversely of the arms and secured to side bars thereof at the junction of the saddles with lower ends of the downwardly bent portions of the side bars, foot rests mounted across the bracing bars, and mechanism for turning the spinner about said post, including an operating element carried by one arm in position for actuation by an occupant of the seat at the outer end of the said arm.
3. On a roundabout, a vertical post, and a spinner comprising a tubular hub loosely mounted about said post, a head plate at the upper end of said hub, arms extending radially of the post and each having side bars connected at their outer ends and having their inner ends secured to the head plate, said side bars being formed of angle metal having downwardly extending side flanges and being bent in spaced relation to their outer ends to form downwardly extending portions and a saddle projecting outwardly therefrom, seats upon said saddles, handle bars mounted across said arms inwardly of the downwardly bent portions of their side bars, bracing bars secured at inner ends to the lower end portion of said hub and extending outwardly at an upward incline and having their outer ends secured to cross bars extending transversely of the arms and secured to side bars thereof at the junction of inner ends of the saddles with the downwardly bent portions of the side bars, foot rests mounted across the bracing bars, a ratchet member rigid upon the post above the head plate, a lever loose about the ratchet member and having a pawl engaging teeth of said ratchet member, an operating lever pivoted to a side bar of one

arm and extending across the said arm and projecting from the opposite side bar thereof, a strip mounted longitudinally of the last mentioned side bar and overlying the operating lever to guide swinging movement thereof, and a reach rod pivoted at one end to the outer end of the first lever and having its other end pivoted to the operating lever.

4. In a roundabout, a vertical post, and a spinner including a hub freely rotatable about said post, arms extending from said hub radially thereof and braced against downward tilting, seats at outer ends of said arms, said post projecting upwardly from said hub and having its upper end portion reduced and squared to form a neck, a ratchet member mounted about the neck said neck having a threaded socket leading from its upper end, and having upper and lower flanges about its periphery and teeth between the flanges, a cap upon the upper end of the neck having its lower end resting upon the ratchet member, a screw passing through the cap and

into the threaded socket in the neck to hold the cap in place, a lever loose about the ratchet member between the flanges thereof and carrying a spring-pressed pawl engaging teeth of the ratchet member, an operating lever pivoted to one arm within reach of the occupant of the seat of the said arm, and a pitman rod connecting the operating lever with the first mentioned lever.
